UNITED STATES PATENT OFFICE.

LAYARD CAMPBELL, OF NEW YORK, N. Y., ASSIGNOR, BY MESNE ASSIGNMENTS, TO TWIST SEAL COMPANY, OF CHICAGO, ILLINOIS, A CORPORATION OF DELAWARE.

WIRE-STRAPPING TOOL.

Application filed April 14, 1920. Serial No. 373,708.

To all whom it may concern:

Be it known that I, LAYARD CAMPBELL, a citizen of the United States, and a resident of the city of New York, borough of Manhattan, in the county and State of New York, have invented certain new and useful Improvements in Wire-Strapping Tools, of which the following is a full, clear, and exact description.

Among the principal objects which the present invention has in view are: To employ continuous, unshaped wire for strapping or reinforcing crates or other forms of packages for transportation; to perform the operation of strapping quickly; to reduce the weight of the tool by which the strapping is accomplished; to provide strength for tightening the strap on the package before tying the same; and to simplify and cheapen the construction of the tool.

Drawings.

Figure 1 is a side view showing fragments of a tool of the character mentioned, constructed and arranged in accordance with the present invention, showing in conjunction therewith a crate and wire looped thereabout, prior to closing or tightening the same on the crate around which it has been passed, the broken lines of said figure illustrating the position of the take-up lever and of the wire strap when the lever is thrown to the retracted position;

Figure 2 is a detail view on enlarged scale, showing fragments of the take-up lever and tool handle, together with the twisting head with which the tool is provided; and

Figure 3 is an edge view of the same.

Description.

Heretofore the usual practice has been to employ bale wires or wires having a loop formed at one end thereof for strapping crates or similar articles. Machines and tools have been employed for handling the bale wires, for drawing the straight or un-looped end thereof through the loop provided, and for over-turning the unlooped end upon the loop to form a second loop. One objection has existed to this form of strapping, in that the tie or loop has been loosened, or the wire has been bent in drawing it up, with the result that it is liable to break in transit, and loosen the strap with

which the crate has been bound. Also the tie formed by over-turning the secondary loop has been unsatisfactory in that it is easily opened and loosened.

Another form of strap has existed where the straight ends of the wire strap have been drawn together, and twisted upon each other lengthwise of the strap. The tools employed for accomplishing this have been objectionable in that they have been exceedingly heavy, thereby taxing the endurance of the mechanic. And furthermore, they have lifted the joined end of the strap from the crate, to permit the making of the tie, so that when released from the machine the strap is relaxed upon the package.

The objections above mentioned are sought to be avoided by the use of the present tool, wherein a handle 8 has a laterally-extended foot 9, wherein is pivoted a head 10. The pivotal connection for the head 10 with the foot 9 is formed by the hollow stud 11, the end 12 whereof is over-turned to hold the head 10 permanently connected with the handle 8. The stud 11 is tubular to form a passage through which the strapping wire A is passed. The tubular passage in the stud 11 opens into the transverse slot 13, wherein are pivoted the pulleys 14.

At 25 I have illustrated a lever which is pivoted to the handle 8 at 26. Lever 25 carries a roller 15 and a dog 16, the latter being pivoted to the lever at 17.

The wire A is delivered on a reel or other bulk supply, and is threaded between the flange roller 15 and the toothed end of the dog 16. The dog 16 is pivoted by the pin 17, whereon it is rocked by the weighted end 18. The flange 19 of the roller 15 serves to guide the wire A. A further guide is furnished for the wire A by the pin 20, which also serves as the side of a detent jaw when cooperating with the dog 21. The dog 21 is pivotally mounted by the pin 22 on the handle 8, and is normally set in operative position by the weighted end 23 with which the said dog is furnished.

Adjacent the pin 20 and dog 21 is an abutment pin 24, which limits the extension of the free end of the wire A as the same is returned through the passage in the stud 11, and between the pin 20 and dog 21.

In operation the wire A is first threaded between the roller 15 and the dog 16. This

operation is facilitated by rocking the take-up lever 25 on its pivot bolt 26, to a position where the dog 16 is open, or the toothed end is removed from engagement with the roller 15. The wire is then passed above the pin 20, through the opening in the stud 11, and through the slot 13 between the pulleys 14. From this point it is extended around the crate B, in the loose form shown by full lines in Figure 1 of the drawings, and the free end is returned and threaded back through the slot 13, between the pulleys 14 through the stud 11 and between the pin 20 and the dog 21, until it is arrested by the end of the wire A engaging the abutment pin 24. Thereafter the end of the wire A is held by the dog 21 against retraction.

The operator now draws backward the lever 25, with the result that the dog 16 rocks to position to engage the wire A, and to hold the same against further passage therebetween. The wire A now being held by the lever 25, the slack of the wire A, where it extends around the package B, is taken up, as shown by the dotted lines in Figure 1. When the wire is drawn in this position, the operator raises the lever 25 to the upright position, the dog 16 releasing the wire A, which is, therefore, not fed forward as the dog moves forward. At the proper position the lever 16 is again retracted, the dog 16 taking a fresh bite on the wire A, and drawing on the loop about the package B more tightly.

This operation is repeated until the loop about the package B is contracted as tightly as may be desired. The lever 25 is at this time in a position substantially parallel with the handle 8. The operator now holding the lever and handle 8 in their relative positions, turns the tool about the stud 11, the head 10 being non-rotatively held by the wire A as the same extends in opposite directions to opposite sides of the package B. As the tool is revolved, the portions of the wire within and adjacent the head 10, up to the pin 20, are twisted upon each other. If the rotation is continued, a very tightly and securely twisted section is obtained.

When this has been effected, the wire A is severed at a point adjacent to the pin 20, and the tool is then withdrawn from engagement with the twisted section of the said wire, which then extends perpendicularly to the side of the package. This is corrected by means of a hammer or other tool, which is used to beat down the standard twisted section, or to lay the same parallel with the wire strap at either side of the junction of the twisted ends.

It will be noted that the wire A is still engaged by the roller 15, and dog 16, so that the tool is ready for the next operation.

It is obvious that the herein disclosed

tool may be constructed of light material, so that undue fatigue is avoided as far as the mechanic is concerned. It is also obvious that when finished, the tie performed by said tool has not been performed by lifting the wire constituting the strap. Therefore, when released, the strap is as tight as when it was drawn up. Also it is obvious that by using a continuous wire, such as is delivered in reels or spools, the length of the strap conforms to the work performed, or to the size of the package, which is being secured, resulting in the saving of large quantities of wire employed in this art.

Claims.

1. A tool as characterized comprising a guide member for aligning the sections of a wire strap adjacent the terminal thereof; a handle pivotally connected with said guide member for rotation thereon; means mounted on said handle for holding said terminal; and means mounted on said handle for engaging the wire from which said strap is formed, said means being adapted to engage said wire step by step.

2. A tool as characterized comprising a handle for holding one end of a looped wire; a lever pivotally mounted on said handle for holding the opposite end of said looped wire; a head pivotally mounted on said handle for guiding the ends of said looped wire; said head being adapted to guide the wire while said handle and lever are rotated about the pivotal connection of said head for twisting the ends of said wire together.

3. A tool of the class described, comprising parallel pulleys adapted to lie against a surface of a package and to guide the terminals of a wire loop extended around said package, a head carrying said pulleys, a passage through said head, said passage being disposed with its axis substantially at right angles to the axes of said pulleys, a handle mounted on said head for rotation around the axis of said passage, and means carried by said handle and located at one end of said passage adapted to grip and space wire loop terminals which extend through said passage from the opposite side thereof.

4. A tool of the class described, comprising parallel pulleys adapted to lie against a surface of a package and to guide the terminals of a wire loop extended around said package, a head carrying said pulleys, a passage through said head, said passage being disposed with its axis substantially at right angles to the axes of said rollers, a handle mounted on said head for rotation around the axis of said passage, and means carried by said handle and located at one end of said passage adapted to grip and space wire loop terminals which extend

through said passage from the opposite side thereof, said gripping and spacing means comprising a lever pivoted to said handle substantially as and for the purpose set forth.

5. A tool of the class described, comprising a tubular guide member, a handle rotatably mounted on said guide member and extending substantially parallel to the axis

10 thereof, means on said handle for gripping one end of the wire loop, a take-up lever pivotally secured to said handle, and a dog on said take-up lever for gripping the other end of the wire loop.

15 6. A tool of the class described, including a guide member having a tubular portion, a handle mounted on said tubular portion for rotation around the axis thereof, a take-up lever pivotally secured to said handle, and

20 a wire gripping dog on said take-up member.

7. A tool of the class described, comprising

ing a head having a passage therethrough, and adapted to lie in contact with the surface of the package with the axis of said 25 passage at substantially right angles to said surface, a handle carried by said head and extending substantially parallel to the axis of said passage, a take-up lever pivotally secured to said handle, and wire gripping 30 means carried by said take-up lever.

8. A tool of the class described comprising a head having a passage therethrough and adapted to lie in contact with the surface of a package with the axis of said 35 passage substantially at right angles to said surface, a handle rotatably mounted on said head, means carried by said handle for gripping one end of a wire loop, a take-up lever carried by said handle, and means on said 40 take-up lever for gripping the other end of the wire loop.

LAYARD CAMPBELL.
